(57) CLAIM

The ornamental design for a Holy Bible trailer hitch cover, as shown and described.

DESCRIPTION

FIG. 1 is a perspective view of a Holy Bible trailer hitch cover showing our new design;

FIG. 2 is an enlarged front elevation view thereof;

FIG. 3 is an enlarged top plain view thereof;

FIG. 4 is an enlarged left side elevation thereof;

FIG. 5 is an enlarged side view thereof;

FIG. 6 is an enlarged rear plain view thereof; and,

FIG. 7 is an enlarged rear view thereof.

The broken line showing of environment in FIG. 1 is for illustrative purposes only and forms no part of the claimed design.
